United States Patent Office.

P. H. KNOBLOCK, OF WYANDOTTE, KANSAS.

Letters Patent No. 79,481, dated June 30, 1868.

IMPROVED CAR-COUPLING.

The Schedule referred to in these Letters Patent and making part of the same.

TO WHOM IT MAY CONCERN:

Be it known that I, P. H. KNOBLOCK, of Wyandotte, in the county of Wyandotte, and State of Kansas, have invented a new and valuable Improvement in Car-Couplers; and I do hereby declare that the following is a full, clear, and exact description of the construction and operation of the same, reference being had to the annexed drawings, making a part of this specification, and to the letters and figures of reference marked thereon.

Figures 1 and 2 are exterior views of my device, and

Figure 3 is a longitudinal section thereof.

The object of my invention is to provide better means than have heretofore been known or used for coupling and disconnecting railroad-cars, without obliging the operator to risk life or limb by passing between such cars while the coupling and detaching process is being carried on.

I call that portion of my device represented by the letters A and B, respectively, the upper and lower jaws of the coupler, the jaw B being stationary, and the jaw A pivoted thereto at the point C, as shown. The letter D is a slat, adjusted to the top of jaw B for the purpose of holding the stop E in its place.

The stop E is fastened with a screw, in a mortise, under the lower side of slat D, in the manner represented. Its office is to serve as a stop or spring, to prevent the jaw A from being opened more widely than is necessary, and to restore said jaw to its proper place after the object for which it was opened has been accomplished.

The letters G are levers, pivoted to the sides of jaw A in the manner shown. The lower ends of these levers respectively rest upon the upper side of the jaw B at the point, and in the manner represented, and they are united at their upper ends, above jaw A, by a cross-bar, H, in which I attach the cord by which the jaw A is drawn upward. It will be observed that, inasmuch as these levers G are pivoted to the jaw A, the lower ends thereof are allowed to move forward upon the upper side of jaw B while the lifting process is being carried on, and to move backward thereon, while the said jaw is being restored to its place.

The letter K is a swinging frame, composed of three pieces, and forming three segments of a square, with the top removed. This frame is slotted near the upper ends of the side pieces thereof, and a rod passes through said slots, and into the sides of jaw A, as shown at a'. This frame is designed for lifting the coupling-hook, hereinafter mentioned.

The letter M is a coupling-hook, constructed in the form shown in fig. 3. Its immediate office is to form the connection between the cars, and it is by releasing this hook from the jaws of the coupler that the cars are detached.

The foregoing comprises a sufficient description of my invention, except that the lower segment of frame K is united with a platform or table, as shown at c, and the front ends of jaws A and B, respectively, are bevelled inwards, as shown in fig. 3. This bevel-form is designed to furnish and serve as a guide for the coupling-hook when the same is being used for connecting the cars; and to allow space for the necessary oscillations thereof, while the cars are in motion.

By means of the devices shown and described, the conductor or brakeman is enabled to disconnect the cars by pulling a cord attached to the cross-bar H, and it will readily be perceived that the connecting-process may be carried on without passing from the platform.

What I claim as my invention, and desire to secure by Letters Patent, is—

A car-coupler, having jaws A and B, slotted frame K, cross-bar H, with cord attached as described, levers G, and hook M, constructed, combined, and arranged substantially as specified.

PH. KNOBLOCK.
